[57] ABSTRACT

A therapeutic device for reducing capillaries in and around the eye areas by the application of ice or a very cold liquid in a flexible bladder that continuously conforms in shape to the skin areas of the user while the ice or cold liquid absorbs heat from the skin areas.

ATTORNEY

EYE DEVICE

BACKGROUND OF THE INVENTION

This invention relates generally to therapeutic devices for the improvement and conditioning of facial skin tissue and in particular to an eye-temple skin area applicator that absorbs heat from skin tissue including the eye lids and surrounding facial areas including the temple areas. Similar devices in the past have had a serious drawback in that proper and thorough heat absorption has not been accomplished because the applicator was poorly fitted with respect to the contour of user's face adjacent the eyeball dip and groove, especially when used with a frozen medium for heat absorption.

Applicant's invention provides for an applicator that conforms to the shape of the user's facial areas throughout the entire use time as the heat absorption medium changes state, insuring continuous skin contact for maximum efficiency.

BRIEF DESCRIPTION OF THE INVENTION

A therapeutic heat absorption facial applicator comprising a sealed bladder having a rigid surface portion on a first side and a flexible surface portion on a second opposite side, said flexible portion for contacting the facial skin of a user, said bladder containing a liquid such as water which can be frozen, said rigid surface portion symmetrically shaped in a facial contour corresponding to the eye and surrounding areas including the temples of a user. The liquid in the bladder is frozen so that the flexible portion is shaped in a contour similar to the rigid portion, thus allowing the flexible portion to be fitted in place adjacent the user's facial skin. As the inner medium melts, the liquid adjacent the flexible surface assumes the shape of the adjacent user's facial contour insuring complete skin contact.

It is an object of this invention to provide an improved therapeutic device for the treatment of skin tissue adjacent the eye areas.

It is another object of this invention to provide a heat absorption device that insures thorough contact with the skin areas adjacent the eyes and temples of the user.

And yet another object of the invention is to provide a device for reducing capillaries in and around the eye areas for inducing a soothing and restful feeling in the user.

In accordance with these and other objects which will be apparent hereinafter, the instant invention will now be described with particular reference to the accompanying drawings.

BRIEF DESCRIPTION OF THE DRAWINGS

FIG. 1 is a plan view in cross-section of applicant's invention.

FIG. 2 is an elevation cross-section of applicant's invention.

FIG. 3 is a partial cross-section or elevation showing applicant's invention in operation against the skin area surrounding the eye of the user.

FIG. 4 is a perspective view of applicant's invention.

PREFERRED EMBODIMENT OF THE INVENTION

Referring now to the drawings and in particular to FIG. 1, applicant's device 10 is shown comprising a rigid, contoured surface 12 coupled about its perimeter

to a flexible member 14 forming sealed, twin chambers or bladders partially filled with fluid 16. The bladders are separated by a rigid nose bridge 18 which is shaped for the concave side to rest against the user's nose skin area. The bridge 18 may be filled with fluid 16 if desired, making the entire bladder one large chamber. However, in the preferred embodiment, the bridge 18 is a rigid member connecting the adjacent bladders symmetrically. Each bladder is shaped and sized to fit over a human eye and the surrounding area from adjacent the nose across to the temple area, symmetrically on each side of the bridge 18. The rigid surface 12 forms substantially a hemisphere on one side of device 10 while the flexible member 14 forms the other hemisphere half. Rigid surface 12 may be composed of a hard rubber or semi-resilient material that holds its shape or will return to an original shape if deformed by an outside force. Surface 14 on the other hand may be of a thin, flexible material such as Neoprene rubber or polyurethane sheet that assumes the shape of the object it is placed in contact with. The two surfaces 12 and 14 are heat sealed or glued together to form hermetically sealed chambers that do not allow liquid 16 to escape.

FIG. 2 shows rigid surface 12 jointed to flexible surface 14 along the edge of 12A of surface 12.

FIG. 4 shows the front overall shape of device 10 with curved end portions to wrap around extending to the temple areas of the user, the rigid surface 12 being employed away from the user's skin, while flexible portion 14 is placed directly on the eye of the user.

FIG. 3 shows applicant's invention in operation in contact with facial area 20. Prior to application of device 10, the device was placed in a freezing compartment with rigid surface down and the flexible surface manually shaped to provide concave impressions to allow fitting to the facial contour of a user. Medium 16 is frozen into a contour shape. Upon removal of the device from the freezing compartment and contacting facial area 20, the immediate adjacent surface layer 16A melts from absorbing heat from the skin. The liquid layer readily assumes the shape of the adjacent skin surface, thus providing complete point to point contact between the surface 14 and the user's face. The device 10 may be kept in place until all of the ice 16B has melted.

Although water has been shown as the liquid medium, any other liquid having comparable melting temperature points could be used.

Because of applicant's invention, the entire area around the eyes including the loose skin below the lower eyelid may be cooled to reduce capillaries providing a soothing and restful feeling and improved appearance of the user.

The instant invention has been shown and described herein in what is considered to be the most practical and preferred embodiment. It is recognized, however, that departures may be made therefrom within the scope of the invention and that obvious modifications will occur to a person skilled in the art.

What I claim is:

1. A therapeutic device for absorbing heat from skin tissue surrounding human eyes and from the closed eyelid coverings of human eyes of a user comprising: a stiff outer wall in the general form of a pair of bifocal eye glasses to cover the eyes of a user, said outer wall includes a right and left portion with an

intermediate nose bridge portion to hold said therapeutic device on the user,
a flexible inner wall connected to said stiff outer wall to form at least one liquid container, said flexible inner wall sized and having a variable contour to 5 make contact with the entire closed eyelid of each

eye and the skin tissue surrounding each eye of a user, and
liquid in each container for absorbing heat from the eyelids and skin tissue areas.
